UNITED STATES PATENT OFFICE.

ALEXANDER SZASZ, OF HINSDALE, ILLINOIS.

CHAIR-OPERATED CHURN.

1,153,272.

Specification of Letters Patent. Patented Sept. 14, 1915.

Application filed May 17, 1915. Serial No. 28,655.

To all whom it may concern:

Be it known that I, ALEXANDER SZASZ, a subject of the King of Hungary, residing at Hinsdale, in the county of DuPage and State 5 of Illinois, have invented certain new and useful Improvements in Chair-Operated Churns, of which the following is a specification.

This invention relates to new and useful 10 improvements in chair operated churn.

The primary object of this invention is to provide an inexpensive means for operating a churn so that the butter making process may be carried on while the operator 15 is comfortably seated in a rocking chair.

A further object of the device is to provide a rotary dasher for a stationary churn and a rocking chair actuating means for the said dasher.

With these general objects in view and others that will appear as the nature of the invention is better understood, the same consists in the novel combination and arrangement of parts hereinafter fully described, 20 illustrated in the accompanying drawings and pointed out in the appended claim.

In the drawings forming a part of this application and in which like designating characters refer to corresponding parts 30 throughout the several views:—Figure 1 is a central longitudinal sectional view taken through the device, a portion of the operating mechanism including the rocking chair being shown in elevation, and Fig. 2 is a vertical transverse sectional view taken on lines II—II of Fig. 1.

It will be noted that a barrel churn 10 is herein illustrated, the same being mounted stationary upon supporting legs 11 by means 40 of two opposite cylindrical posts 12 secured to the opposite ends of the barrel and arranged upon the central longitudinal axis thereof, the said churn being provided with a closure lid 13 in the top thereof.

A dasher 14 in the form of a plate is provided within the churn having an operating shaft 15 extending longitudinally thereof and fixedly secured thereto, the said shaft 15 being revolvably journaled in the central 50 bores 16 of the said posts 12.

A rocking chair 17 is adapted for operat-

ing the churn by revolving the dasher 14 thereof by means of mechanism hereinafter set forth. A bracket 18 is positioned upright between the churn and the chair, the 55 same being secured to the foot 19 of one of the supporting legs 11. A rocking beam 20 is pivoted in the top of the bracket 18 by means of a pin 21 and is provided with opposite enlarged ends 22 and 23 respectively, 60 each of which is provided with a central longitudinal slot 24.

The front leg 25 of the rocking chair is provided with a bolt 26 extending through the slot 24 of the beam end 23, while a similar bolt 27 extends through the slot of the opposite end 22 and pivotally connects an operating rod 28 to the said rocking beam. One end of the dasher shaft 15 is provided 70 with a crank 29 and a link 30 is revolvably mounted at one end upon the said crank and at its other end is connected by means of a hinged joint 31 with the upper end of the operating rod 28.

The dasher 14 is provided with a plurality of perforations 32 and it will be at once apparent that upon a rocking of the chair 17 to and fro, the end 23 of the rocking beam 20 will be alternately lowered and raised, thereby communicating opposite 80 movement to the opposite end 22 thereof. The rod 28 is thereby reciprocated between spaced guide rollers 33 outwardly projecting from the supporting leg 11 and thus the dasher shaft crank 29 is operated through 85 the agency of the connecting link 30. The churn dasher 14 is thus forcibly revolved within the churn 10 continuously and simultaneously with the rocking action of the chair 17 so that the churning operation may 90 be effected by any person rocking the chair while seated therein.

While the form of the invention herein shown and described is what is believed to be the preferred embodiment thereof, it is 95 nevertheless to be understood that minor changes may be made in the form, proportion and details of construction without departing from the spirit and scope of the invention as set forth in the appended claim. 100

What is claimed as new is:—

A crank shaft operating device compris-

ing a base, an oscillating rocker parallel to said base, a lever pivoted to the base, means for loosely connecting one end of said lever to the rocker, a rod guide supported on said base, a rod reciprocable in said guide, means for loosely connecting the rod to the remaining end of the lever, a pitman pivoted

to the upper end of the rod and provided with means for connection to the crank on the crank shaft.

¹⁰ In testimony whereof I affix my signature.

ALEXANDER SZASZ.
